FOOT IMPRESSION DEVICE

William P. Koppe, Chicago, Ill., assignor to The Scholl Mfg. Co., Inc., Chicago, Ill., a corporation of New York

Application April 2, 1934, Serial No. 718,671

11 Claims. (Cl. 282—1)

My invention relates to foot impression devices and is concerned more particularly with providing a unitary and easily transportable apparatus for the taking of foot impressions in order to secure information respecting the configuration of the foot as well as its size.

In the fitting of footwear, the selection of the proper shoe for any particular person should be based upon accurate information respecting the foot and this knowledge should not only include the ordinary data on the length and width of the foot, but also precise information regarding any abnormalities thereof, such as may be produced by fallen arches, enlarged joints, callouses, and like ailments. Shoe measuring sticks are now commonly employed for determining foot widths and lengths, and there are also other devices for taking impressions of the foot by pressing the latter against an ink-carrying member which in 10 turn contacts a sheet of paper, so that a shoe retailer, for example, can properly fit shoewear. A device of the latter type is illustrated in United States Letters Patent to Rosino No. 1,225,500, dated May 18, 1917, and the present invention relates to a device of the same character, but embodies several improvements thereover.

One object of my invention is to provide a relatively thin, compact foot impression device which is adapted for easy handling and transportation.

30 A further object is to provide a device of the character indicated in which the ink-carrying member is fixed at its opposite ends and directly over the impression-receiving paper, thereby obviating the necessity for a spring-retracted roller 35 on which the member is wound and also moving the member to impression-taking position, both of these features being characteristic of the prior art.

40 A further object is to provide a device in which the sheets of paper, on which the impressions are made, are carried in a drawer which is shiftable to one position in which the paper is disposed below the ink-carrying member to receive the impression, and to another position in which the 45 paper is either exposed for observation, or for convenient removal from the drawer.

50 A further object is to provide a device in which the inking roll is carried by the drawer and which is adapted to apply ink to the ink-carrying member by the inward and outward movements of the drawer.

55 A further object is to so position the inking roll relative to one fixed end of the ink-carrying sheet that the latter is substantially parallel, and relatively close, to the paper that receives the im-

pression when the drawer is in impression-taking position, thereby avoiding any necessity for applying considerable pressure in order to make an intelligible impression, since such action is frequently objectionable and also quite difficult, particularly where the person has weak feet or legs, or in the case of a child.

These and further objects of my invention will be set forth in the following specification, reference being had to the accompanying drawing, 10 and the novel means by which said objects are effectuated will be definitely pointed out in the claims.

In the drawing:

Figure 1 is a plan view of my improved device 15 as it appears to the user when a foot impression is being taken.

Fig. 2 is a section along the line 2—2 in Fig. 1, looking in the direction of the arrows.

Fig. 3 is a section, similar to that shown in Fig. 2, but showing the drawer in extended position for the purpose of removing the paper sheet on which the impression has been made.

Fig. 4 is a section along the line 4—4 in Fig. 2, looking in the direction of the arrows, and showing 25 the construction details of the drawer.

Fig. 5 is an elevation, partly in section, of one end of the inking roller.

Referring to the drawing, the numeral 10 designates a box-like frame which comprises a base 11 and a top 12 which is spaced from the bottom by marginal wall blocks 13 which extend around three sides of the frame and are eliminated on the fourth side to provide an opening 14. The top 12 is provided with an opening 15 which is preferably rectangular in outline and which exposes an ink-carrying member, such as a rubber apron 16, which extends across the opening beneath the top 12 and at one end is clamped to the rear wall block 13 by a strip 17 and at the opposite end to the underside of the top 12 by a strip 18.

A drawer 19 is slidable in the frame 10 through the opening 14 and comprises a bottom 20 and upstanding side walls 21. As clearly shown in Fig. 4, the bottom and walls are preferably integrally formed from a single metallic sheet. The front end of the drawer 19 is closed by a block 22, to which a convenient handle 23 may be attached for operating the drawer, while adjacent the opposite end of the drawer, an ink carrying roll 24 is bridged between the side walls 21.

Preferably, the roll 24 is composed of a hollow cylinder 25 which is overlaid by a suitable inking surface, such as a silk covered felt pad 26, one example of which is disclosed in the aforesaid

Rosino patent, and the cylinder 25 may be provided with perforations 27 in order to insure a proper and adequate flow of ink to the inking surface. The ends of the cylinder 25 are provided with pintles 28 that are revolvably mounted in open ended slots 29 provided in the side walls 21, these slots preferably opening upwardly, as clearly shown in Fig. 2. One of the pintles 28 may be conveniently threaded as at 30 into the cylinder 25 in order to permit its ready removal whenever it becomes necessary to replenish the ink supply in the cylinder. A pressure gun may be employed for this purpose, or the ink container, such as a collapsible tube, may be attached directly by threading its end into the cylinder 25.

The apron 16 extends over the top of the inking roll 24 and is then directed downwardly to pass beneath a guide roll 31 whose pintles are received within open ended slots 32 that are also provided in the side walls 21. As shown in Fig. 2, these slots open downwardly and the tension of the rubber apron 16 maintains the guide roll in the indicated position. It will be particularly noted that the relation of the roll 31 to the roll 24 is such that the apron 16 is caused to contact with a very appreciable portion of the surface of the inking roll in order to insure that the latter will convey a working supply of ink to the under surface of the apron.

On the opposite side of the inking roll from the guide roll, there is provided a distributing fin 33 which is suitably supported on the bottom 20 and extends upwardly to contact with the underside of the paper 16.

A pair of spaced strips 34 are conveniently recessed in the bottom 11, below the drawer 19, and each of the strips is provided with a resilient tongue 35 which is bent upwardly out of the plane of the associated strip. Each of these tongues is intended to engage with an aperture 36 provided in the drawer bottom 20, when the drawer has been moved to the position shown in Fig. 3, thereby limiting the outward extending movement of the drawer.

In taking a foot impression, a suitable impression receiving member, such as a pad of paper 37, is rested on the bottom of the drawer, when the latter is in the extended position shown in Fig. 3.

Preferably, the inside marginal dimensions of the drawer are such that they closely approximate the marginal outline of the paper pad, so that one end of the drawer, for example, may be conveniently employed as a heel stop. The paper sheets are customarily lined or marked to indicate foot sizes.

The drawer is then moved inwardly toward the position shown in Fig. 2, and this operation, due to the frictional contact between the apron 16 and the inking surface of the roll 24, causes a rotation of the latter roll and consequently an application of ink to the under surface of the apron. The ink so applied is evenly distributed over the surface of the apron by the fin 33.

The foot is then pressed against the apron and the pressure is continued until the apron contacts with the pad 37, as indicated by dotted lines in Fig. 2. The impression so made will be somewhat shadowy in appearance and will thereby indicate abnormalities of the foot, because those parts which protrude the most will produce the darkest areas on the paper because of the increased pressure. Many ailments of the foot may thus be effectively ascertained and a proper decision made regarding the style of footwear. The sheet of

paper on which the impression is made may be removed after shifting the drawer to the position shown in Fig. 3.

The provision of spacing the apron just slightly above the upper surface of the pad 37 is one of the important features of this invention, because it substantially lessens the amount of pressure required to effect an adequate impression, owing to the short distance through which it is necessary to displace the apron. Accordingly, this device is highly useful for the taking of impressions of persons with weak feet or legs, or children, since slight pressures will still secure intelligible impressions.

Aside from the foregoing advantage inherent in the device, the latter is characterized by compactness and an absence of any necessity for employing the customary spring retracted roller over which the rubber apron has heretofore been wound. In addition, the drawer 19 provides a very convenient storage space for a number of sheets which comprise the pad 37 and these sheets may be allowed to remain in the drawer until the entire pad is exhausted.

I claim:

1. A foot impression device comprising a frame, ink-carrying means adapted to be pressed by a foot, and a member adapted to support a part for receiving impressions and shiftable in the frame to a position adjacent the ink means for taking impressions and to another position exposing the part.

2. A foot impression device comprising a frame, an ink-carrying member adapted to be pressed by a foot, a drawer adapted to support a part for receiving impressions and shiftable in the frame to impression-taking and exposing positions, respectively, and inking means carried by the drawer and adapted to apply ink to the member during the movement of the drawer.

3. A foot impression device comprising a frame, an apron secured at its opposite ends to the frame and adapted to be pressed by a foot, a drawer adapted to support a part for receiving impressions and shiftable in the frame to impression-taking and exposing positions, respectively, and an inking roller rotatably mounted in the drawer and adapted to apply ink to the apron during the movement of the drawer.

4. A foot impression device comprising a frame, an apron secured at its opposite ends to the frame and adapted to be pressed by a foot, a drawer adapted to support a part for receiving impressions and shiftable in the frame to impression-taking and exposing positions, respectively, an inking roller rotatably mounted in the drawer and adapted to apply ink to the apron during the movement of the drawer, and a fin carried by the drawer and contacting with the apron to substantially evenly distribute the applied ink.

5. A foot impression device comprising a frame, an apron secured at its oposite ends to the frame and adapted to be pressed by a foot, a drawer adapted to support a part for receiving impressions and shiftable in the frame to impression-taking and exposing positions, respectively, an inking roller rotatably mounted in the drawer and adapted to apply ink to the apron during the movement of the drawer, and a guide roller positioned relative to the inking roller to cause the apron to contact with an appreciable portion of the inking roller surface.

6. A foot impression device comprising a frame, an apron secured at its oposite ends to the frame and adapted to be pressed by a foot, a drawer

adapted to support a part for receiving impressions and shiftable in the frame to impression-taking and exposing positions, respectively, an inking roller rotatably mounted in the drawer and
5 adapted to apply ink to the apron during the movement of the drawer, and a guide roller positioned relative to the inking roller to cause the apron to contact with an appreciable portion of the inking roller surface, said guide roller being mounted in open-ended slots in the drawer and retained therein by the pressure of the apron.

7. A foot impression device comprising a frame, an apron secured at its opposite ends to the frame and adapted to be pressed by a foot, a drawer
15 adapted to support a part for receiving impressions and shiftable in the frame to impression-taking and exposing positions, respectively, and an inking roller rotatably mounted in the drawer and adapted to apply ink to the apron during the movement of the drawer, the top surface of the roller lying in substantially the same plane as that secured portion of the apron remote from the roller when the drawer is in impression-taking position to thereby locate the apron in substantially parallel relation to the impression-receiving means.

8. A foot impression device comprising a frame, an ink carrying member adapted to be pressed by a foot, a drawer adapted to support a part for receiving impressions and shiftable in the frame to impression-taking and exposing positions, respectively, and means for limiting the shifting movement of the drawer.

9. A foot impression device comprising a hollow box having an opening in its top surface for receiving a foot and an opening in one side wall, a flexible, ink-carrying apron extending across the top surface opening within the box and adapted to be pressed by a foot, and a drawer adapted to support a part for receiving foot impressions shiftable in the box through the side wall opening to a position adjacent the apron for taking an impression and retractile to expose 10 the impressed part.

5
10
15
15. A foot impression device comprising a frame, an ink-carrying member adapted to be pressed by a foot, a drawer adapted to support a part for receiving impressions and shiftable in the frame to impression-taking and exposing positions, respectively, and inking means adapted to apply ink to the member during and controlled by the movement of the drawer.

20
20. A foot impression device comprising a frame, an apron secured at its opposite ends to the frame and adapted to be pressed by a foot, a drawer adapted to support a part for receiving impressions and shiftable in the frame to impression-taking and exposing positions, respectively, an inking roller rotatably mounted in the drawer and adapted to apply ink to the apron during the movement of the drawer, and means
25
25 for causing the apron to wrap around an appreciable portion of the inking roller surface. 30
